UNITED STATES PATENT OFFICE.

ALMOND L. CARLOW, OF PROVIDENCE, RHODE ISLAND.

DESIGN FOR A COLLAR-BUTTON.

46,358.

Specification for Design.

Patented Sept. 8, 1914.

Application filed July 13, 1914. Serial No. 850,831. Term of patent 7 years.

To all whom it may concern:

Be it known that I, ALMOND L. CARLOW, a citizen of the United States, residing at Providence, in the county of Providence and State of Rhode Island, have invented a new, original, and ornamental Design for Collar-Buttons, of which the following is a specification, reference being had to the accompanying drawing, forming part thereof.

Figure 1 is a plan view of a collar button showing my design. Fig. 2 is a side view, and Fig. 3 is an end view of the same.

I claim—

The ornamental design for a collar button, as shown.

ALMOND L. CARLOW.

Witnesses:

ADA E. HAGERTY,

J. A. MILLER.
